UNITED STATES PATENT OFFICE.

LEONARD OWEN SMITH, OF PHILADELPHIA, PENNSYLVANIA.

DEVICE FOR HOLDING SILKS OR THREADS.

SPECIFICATION forming part of Letters Patent No. 531,475, dated December 25, 1894.

Application filed October 6, 1894. Serial No. 525,079. (No model.)

To all whom it may concern:

Be it known that I, LEONARD OWEN SMITH, a citizen of the United States, residing in Philadelphia, county of Philadelphia, and State of Pennsylvania, have invented a new and useful Holding Device for Embroidery Silks or other Threads, of which the following is a full, clear, and exact specification.

My invention relates to an improved device for holding embroidery silks or other threads, and consists in the novel arrangement of the parts hereinafter fully set forth and described.

The object of my invention is to provide a means for holding links or skeins of thread, preferably embroidery silks, which will permit the same to be readily exhibited, which will prevent the contents from becoming soiled, snarled or tangled, and which will, when utilized, facilitate the ready removal of one or more threads without disarranging the remaining contents.

My invention is illustrated by the accompanying drawings, in which—

Figure 1 is a front elevation of the card, a detail of the invention. Fig. 2 is a vertical cross-section of the card shown in Fig. 1 with the skein of silk resting thereon. Fig. 3 is a front elevation of the holder, the parts being assembled and the skein of silk in position for use. Fig. 4 is a front elevation of a modification. Fig. 5 is a front elevation of another modification, the lower portion of the case being broken away. Fig. 6 is a front elevation of a modification of the inner card. Fig. 7 is another modification of the same detail.

Similar letters apply to similar parts throughout the several figures.

A is an outer casing or envelope open at both ends.

B is a card of preferably the same configuration but slightly smaller. The case A, is so formed that when the card B is inserted therein, it can only be withdrawn in one direction. Upon the card B a link or skein of thread D, is loosely placed or wound. Toward the upper end of the card B there is by preference formed a recess or perforation E, and in this recess the skein of thread is placed. When the parts are assembled the sides of the skein repose between the inner card and the outer casing so that the thread may not be soiled, tangled or snarled. When the

slightly exposed end of the skein has been cut, as is customary, one or more threads may be readily extracted by exerting a gentle pull (see Fig. 3), and the remaining threads will not be disturbed by virtue of the frictional contact with the casing. To prevent the card B and its contents from being withdrawn from the case A, in the direction of the pull exerted in withdrawing the separate threads, I shape the case and the card, by preference, as shown in Figs. 1, 2 and 3, in which a gentle taper to the said parts is given, thereby making the opening in one end of the casing smaller than the opening at the opposite end.

The essential feature of my invention consists in shaping the case A so that the openings will be, as above referred to, one smaller than the other. As illustrative merely of the manner in which this may be accomplished other than that shown in Figs. 1, 2 and 3, I have submitted modified plans in Figs. 4 and 5.

In Fig. 4 one or both edges of the case A² may approach each other abruptly at an intermediate point in the length of said case, so that a card B² of substantially the same configuration will be prevented from being withdrawn therefrom excepting in one direction.

In Fig. 5, the lower edges of the case A² approach each other abruptly at the lower end of the said case thereby retaining the card B' and thus accomplishing the desired object.

In Figs. 6 and 7 recesses or perforations F' of suitable shape may be provided at the lower or narrower end of the cards B³ B⁴. These recesses are particularly adapted to carry the skein when the same is being inserted into the case.

Having thus described my invention, what I claim, and desire to secure by Letters Patent, is—

1. A device for holding embroidery silk or thread consisting of an elongated card the opposite edges of which incline toward each other, said card carrying longitudinally thereon a skein of thread, with an outer casing enveloping said card and shaped to correspond therewith, said casing being open at the narrower end to permit the threads to be independently withdrawn therethrough, substantially as described.

2. A device for holding embroidery silks or threads consisting of an elongated tapered

card recessed at the broader end and enveloped in a casing of corresponding shape and size, said casing being open at the narrower end to permit threads mounted upon said card 5 to be withdrawn from the holder through the narrower end of the casing without displacing said card, substantially as described.

3. A device for carrying threads consisting of an elongated card the edges of which incline toward each other, said card being re-

cessed as described, a skein of thread longitudinally disposed on said card, with an envelope open at both ends and shaped to correspond substantially to the size of the said card, and surrounding the same, substantially 15 as and for the purpose specified.

LEONARD OWEN SMITH.
